GRILLWORK ARCHITECTURAL PANEL OR SIMILAR ARTICLE

Frank B. Miller, 1842 Ransome Road, Glendale, Calif.

Filed Oct. 15, 1959, Ser. No. 57,940

Term of patent 14 years

(Cl. D54—2)

The figure is a perspective view of a grillwork architectural panel or similar article embodying my new design.

The dominant features of my design reside in the portions shown in full lines.

I claim:

The ornamental design for a grill-work architectural panel or similar article, substantially as shown and described.
